US00D742320S

(12) **United States Design Patent**
Akana et al.

(10) **Patent No.:** US D742,320 S
(45) **Date of Patent:** ** Nov. 3, 2015

(54) **ADAPTER**

- (71) Applicant: **Apple Inc.**, Cupertino, CA (US)
- (72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendörfer**, San Francisco, CA (US)
- (73) Assignee: **Apple Inc.**, Cupertino, CA (US)
- (**) Term: **14 Years**
- (21) Appl. No.: **29/481,729**
- (22) Filed: **Feb. 10, 2014**

Related U.S. Application Data

- (63) Continuation of application No. 29/431,841, filed on Sep. 11, 2012, now Pat. No. Des. 699,188.
- (51) **LOC (10) Cl.** 13-03
- (52) **U.S. Cl.** USPC D13/147
- (58) **Field of Classification Search**
USPC D13/147, 154, 184, 199
See application file for complete search history.

(57) **CLAIM**

The ornamental design for an adapter, as shown and described.

DESCRIPTION

FIG. 1 is a front perspective view of an adapter showing our new design;

FIG. 2 is a rear perspective view thereof;

FIG. 3 is a top view thereof, the bottom view being a mirror image thereof;

FIG. 4 is a left side view thereof;

FIG. 5 is a right side view thereof;

FIG. 6 is a rear view thereof; and,

FIG. 7 is a front view thereof.

The shade lines in the Figures show contour and not surface ornamentation.

The broken lines in the Figures show portions of the adapter that form no part of the claimed design.

1 Claim, 5 Drawing Sheets
